(57) The ornamental design for a meal tray, as shown and described.

DESCRIPTION

FIG. 1 is a top view of the meal tray;

FIG. 2 is a bottom view thereof;

FIG. 3 is a front view thereof;

FIG. 4 is a rear view thereof;

FIG. 5 is a left side view thereof;

FIG. 6 is a right side view thereof; and,

FIG. 7 is a perspective view thereof.

The broken line showing of straps and tray legs are for illustrating the environment of the design only and form no part of the claimed design.
